UNITED STATES PATENT OFFICE.

JOSEPH STREDA, OF LONDON, ENGLAND.

ROCK AND LIKE DRILL.

Application filed December 4, 1922. Serial No. 604,941.

To all whom it may concern:

Be it known that I, JOSEPH STREDA, a citizen of the Czechoslovakian Republic, residing at London, England, have invented certain Improvements in Rock and like Drills (for which I have filed applications in Czechoslovakia on October 3rd, 1921; Great Britain, July 25th, 1922; Germany, September 29th, 1922; Rumania, October 3rd, 1922), of which the following is a specification.

The object of the present invention is to produce a locking device whereby different screw-joined parts of rock and like drills can be effectively prevented from becoming accidentally detached during the work, and the invention consists in the provision of a cylindrical block which is arranged in a cavity in one of the drill parts and which 20 is feathered to the other part so as to be prevented from rotary displacement relative to the same, the block being divided transversely into two parts provided with intermeshing ratchet teeth which allow the 25 upper part of the block to be turned into a position in which it can be locked to the surrounding drill part and which prevent relative rotary displacement of the different elements after such locking.

Fig. 1 of the drawings represents a sectional side view of the device as used for locking the drill to the drill head.

Fig. 2 is an elevation at right angles to Fig. 1,

Fig. 3, a cross-section on the line X—X of Fig. 1,

Fig. 4, an end view on a smaller scale of the upper part of the block,

Fig. 5, a side view of the same part,

Fig. 6, a cross-section on the line Y—Y of Fig. 5,

Fig. 7, a side view of the lower part of the block, and

Fig. 8, a cross-section on the line Z—Z of Fig. 7.

The drill B has at one end a conical, screw-threaded plug C whereby it is secured to a corresponding socket formed in the drill head A. The latter has a cavity 1 above the plug C for the reception of the locking device. This consists of a cylindrical block which is divided, transversely of the axis, into two parts *a* and *b*. The lower part is formed with a shoulder 2 and with a feather 3 for the reception of which corresponding recesses 4 and 5 are made in the

end of the plug C. The feather 3 prevents relative rotary displacement of the parts *a* and *C*. The adjoining faces of the parts *a* and *b* are recessed, and about each of the two recesses 6 and 8 a crown of ratchet teeth is formed. The teeth 7 of the lower part mesh with the teeth 11 of the upper part, but allow relative, right-hand, rotary displacement of the two parts. The upper part *b* has also a transverse slot 10 through which to admit a locking bolt *c* which is passed through a corresponding slot 14 in the drill head A. A groove 9 is turned inside the recess 8 in which to receive the ends of a blade spring 13. This spring is curved so as to bear against the bolt *c* which accommodates the spring in a notch 18. A recess 16 is made in the head A to receive the prismatic bolt head 15. Diametrically opposite the recess 16 there is a recess 17 in which to accommodate a split pin *d* which secures the bolt *c* in position. As the head 15 and the pin *d* do not project beyond the outer surface of the drill head, the latter will have no additional elements to hinder it in its work. The block part *b* is formed with two circumferential rows of drill holes 12 arranged so as to be accessible through the slot 14 of the head A.

Before the drill B is connected to the head A, the block *a*, *b* is placed in position on the plug C, whereupon the latter is screwed together with the block into the head A. When a rigid connection has been obtained, the block part *b* is adjusted by means of a wire or nail, inserted through the slot 14 into the apertures 12, so as to set the slot 10 in alignment with the slot 14. The bolt can then be inserted and fastened by means of the split pin *d*, whereupon the drill B will be effectively locked to the drill head. As the bolt *c* is inserted, the spring 13 snaps into engagement with the notch 18 and will, while pressing the two parts of the block together, retain the bolt even if the pin *d* should happen to be detached. The slot 10 is slightly elongated to allow for slight differences in the main connection and also to permit the upper part *b* to lock freely with the lower part *a*.

With a right-hand screw-thread on the plug C, the ratchet teeth 7 and 11 are set so as to oppose a left-hand movement of the lower block part when the upper block is locked to the drill head. If the plug thread is a left-hand one, the block teeth

are reversed so as to oppose the right-hand movement. When all is connected only a slight upward movement of the part *b* is allowed for so that no appreciable rotary displacement of the two block parts can take place in either direction.

It is evident that with the removal of the pin *d* and the bolt *c* the two screw-joined parts *B* and *C* are unlocked and can be taken apart in the usual manner.

The device, which is not affected by the blows on the tool, can be easily fitted into any existing drill and drill head without altering their external shape. Although shown in connection with a drill and a drill head, the device may be used in any other position on the boring tool where two parts have to be screwed together.

I claim:—

1. A device for locking together two screw-joined parts of a rock or like drill, comprising a cylindrical block divided transversely into two parts and fitted in the cavity of the female drill part, the lower part of the block being feathered to the male drill part so as to be prevented from rotary displacement relative to the latter, the adjoining faces of the block part being formed with intermeshing ratchet teeth preventing relative rotation in the unscrewing direction of the drill elements but allowing the top part to be turned in the opposite direction, a headed lock bolt, the top part of the block and the female part of the drill being slotted for the reception of said lock bolt, a split pin for fastening the bolt in locking position, the female drill part being recessed to accommodate the bolt head and the split pin, a blade spring fitted in the top part of the block so as to bear against the inserted lock bolt and press the block parts together, the bolt having a notch in which to receive the abutting part of the spring, the top part of the block being provided with holes arranged so that they can be reached through the slot in the female drill part for turning said top part into position for admitting the lock bolt after the drill parts have been screwed together.

fitted in the top part of the block so as to bear against the inserted lock bolt and press the block parts together, the lock bolt having a notch in which to receive the abutting part of the spring, and means for turning the top part of the block so as to admit the lock bolt after the drill parts have been screwed together.

2. A device for locking together two screw-joined parts of a rock or like drill, comprising a cylindrical block divided transversely into two parts and fitted in the cavity of the female drill part, the lower block part being feathered to the male drill part so as to be prevented from rotary displacement relative to the latter, the adjoining faces of the block parts being formed with intermeshing ratchet teeth preventing relative rotation in the unscrewing direction of the drill elements but allowing the top part to be turned in the opposite direction, a headed lock bolt, the top part of the block and the female part of the drill being slotted for the reception of said lock bolt, a split pin for fastening the bolt in locking position, the female drill part being recessed to accommodate the bolt head and the split pin, a blade spring fitted in the top part of the block so as to bear against the inserted lock bolt and press the block parts together, the bolt having a notch in which to receive the abutting part of the spring, the top part of the block being provided with holes arranged so that they can be reached through the slot in the female drill part for turning said top part into position for admitting the lock bolt after the drill parts have been screwed together.

JOSEPH STREDA.
